US00D943887S

(12) United States Design Patent (10) Patent No.: US D943,887 S
(45) Date of Patent: * Feb. 22, 2022

(54) SHOE

(71) Applicant: Reebok International Limited, London (GB)

(72) Inventor: Dustin Simone, Boston, MA (US)

(73) Assignee: Reebok International Limited, London (GB)

() Term: 15 Years

(21) Appl. No.: 29/750,211

(22) Filed: Sep. 11, 2020

Related U.S. Application Data

(63) Continuation of application No. 29/672,696, filed on Dec. 7, 2018, now Pat. No. Des. 895,949.

(51) LOC (13) Cl. 02-04

(57)

CLAIM

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the shoe that form no part of the claimed design.

The dot-dash broken lines show boundaries that form no part of the claimed design.

1 Claim, 6 Drawing Sheets
